CLAIM

The ornamental design for a floater for a liquid collection device, as shown and described.

DESCRIPTION

FIG. 1 is a top view of a floater for a liquid collection device, showing the present design;

FIG. 2 is a front view thereof;

FIG. 3 is a left view thereof;

FIG. 4 is a rear view thereof;

FIG. 5 is a bottom view thereof;

FIG. 6 is a rear perspective view thereof;

FIG. 7 is a front perspective view thereof;

FIG. 8 is an enlarged view of the area marked '8' in FIG. 4;

FIG. 9 is an enlarged view of the area marked '9' in FIG. 2;

FIG. 10 is an enlarged view of the area marked '10' in FIG. 6;

FIG. 11 is an enlarged view of the area marked '11' in FIG. 7; and,

FIG. 12 is an exploded view of the liquid collection device showing the floater, the collection device and the collection tube.

The broken lines in the drawings illustrate environment and form no part of the claimed design.
